US00D470464S

(12) **United States Design Patent** (10) Patent No.: **US D470,464 S**
Loiske et al. (45) Date of Patent: ** Feb. 18, 2003

(54) **SET-TOP-BOX**

D414,763 S * 10/1999 Iftikar D14/125
D462,063 S * 8/2002 Bohne D14/125

(75) Inventors: **Janne Loiske**, Turku (FI); **Jorma Pitkonen**, Turku (FI); **Michael Corander**, Mottala (SE)

* cited by examiner

(73) Assignee: **Nokia Corporation**, Espoo (FI)

Primary Examiner—Raphael Barkai

(**) Term: **14 Years**

(74) Attorney, Agent, or Firm—Darby & Darby

(21) Appl. No.: **29/154,585**

(57) **CLAIM**

(22) Filed: **Jan. 25, 2002**

The ornamental design for a set-top-box, as shown and described.

(30) **Foreign Application Priority Data**

DESCRIPTION

Jul. 27, 2001 (FI) M20010442

FIG. 1 is a perspective view of a set-top-box as viewed from the front, showing my new design;

(51) LOC (7) Cl. **14-03**

FIG. 2 is a front elevational view thereof;

(52) U.S. Cl. **D14/125**

FIG. 3 is a right side elevational view thereof;

(58) Field of Search D14/357, 358,

FIG. 4 is a left side elevational view thereof;

D14/125, 496, 188, 239, 242, 432; 348/10,

FIG. 5 is a top plan view thereof;

460, 706, 731; 340/825.03; 455/6.1, 6.2;

FIG. 6 is a bottom plan view thereof; and,

312/223.1

FIG. 7 is a rear elevational view thereof.
